REUSABLE CLAMP FOR BEAM FORMS
Homer T. Dudley, Tulsa, Okla., assignor to H. T. Dudley
Company, Inc., Tulsa, Okla., a corporation of
Oklahoma

Filed Mar. 9, 1964, Ser. No. 350,341
2 Claims. (Cl. 249—18)

This invention relates to a clamp for concrete beam forms. More particularly, this invention relates to a clamp for retaining relatively horizontal beam forms used in building construction and is a continuation-in-part of co-pending application Serial No. 101,771, filed April 10, 1961, issued as U.S. Patent No. 3,162,418, dated December 22, 1964.

A primary object of this invention is to provide reusable apparatus for clamping together relatively horizontal beam forms as particularly used in the construction of multistory concrete structures.

Another object of this invention is to provide a clamp for concrete beam forms which eliminates the need for nails and other fasteners heretofore used in the prior art, and need not be vertically supported.

Another object of this invention is to provide a clamp for concrete beam forms which can be readily assembled and disassembled after set of the concrete and be ready for further use.

A still further object of this invention is to provide a clamp for substantially nailless concrete beam forms which includes a removable and pivotal lever for actuation of the clamp parts to a position where a wedge locked member may be inserted to hold said parts and said forms in that position and the pivotal lever removable to a next clamp.

These and other objects of this invention will become more apparent upon reading the specification and claims when taken in conjunction with the following illustrations of which:

FIGURE 1 is a side elevational view, partly in section of the beam clamp of this invention with respect to typical concrete beam forms which it will retain as shown in transverse cross section.

FIGURE 2 is a perspective view of a first bracket generally used as a part of this invention.

FIGURE 3 is a partial sectional view of an alternate embodiment for a second bracket.

FIGURE 4 is a partial isometric view depicting a typical usage of the bracket of this invention.

Referring now to the drawings, and specifically FIGURES 1 and 2, the apparatus of this invention is adapted to clamp substantially nailless beam form members used as forms or molds for concrete beams. As such, the forms comprise vertical side wall members 10 and 12 spaced apart by internal horizontal bottom member 14. Spacers or kickers 16 and 18 are positioned externally of the vertical side wall members 10 and 12 as shown. In some instances, the kickers 16 and 18 are affixed to the outside of vertical side wall members 10 and 12, although this is not absolutely necessary in the adaptation and the use of this invention, but will merely provide ease of assembly and disassembling of the forms. Typically, these longitudinal members as shown in cross section in FIGURE 1 will be supported by spaced T-brace members (not shown) extending from the bottom of the beam form members shown downward to the floor or ground. Typi-

2

cally the construction T-brace members are those described in the aforesaid co-pending application S.N. 101,771. Heretofore, these parts shown in FIGURE 1 and the vertical T supports have been nailed together as a means of retaining them in their position. However, it became readily apparent that the disassembly of said parts would very often destroy their reuse. Accordingly, the clamp and means of this invention is devised to obviate that problem.

10 The clamp basically comprises a horizontal slide bar 20 which can be tubular in form, such as rectangular or round in cross section. The slide bar includes a multiplicity of horizontal openings extending across the full diameter of the slide bar and spaced along the length thereof as shown. At one end, as shown, a pin 24 extends through the last most opening outwardly each side of the horizontal slide bar 20, for use with the removable pivot lever as hereinafter described. At spaced intervals along the length of the horizontal slide bar are a 15 plurality of vertical slots 26 which likewise extend through the horizontal slide bar which represent the various locking positions for the clamp members.

20 Adjacent the end opposite the pin member 24 is a first bracket generally designated by the numeral 28. The bracket includes a support member 30 which is adapted to be telescopic about the horizontal slide bar 20 to one of a multiplicity of positions thereto and locked by the placement of a key or pin 34 through openings 32 of the first bracket which coincide with openings 22 of the horizontal slide bar. In some instances it may be desired to permanently affix the first bracket to the horizontal slide bar in those instances where there will be very little transverse dimensional change in the beam forms. Extending upwardly from the support member 30 is an 25 angle bracket 36 having a vertical and a horizontal portion as shown for supporting connection with kicker 16. The angle bracket 36 is supported to member 30 by a structural gusset 38.

30 Adjacent the end having pin 24 is a second bracket 40 generally designated by the numeral 40. This bracket includes a support member 42 which is adapted to be telescopic about horizontal slide bar 20. The support member 42 may include horizontal openings 44 which will be adapted to coincide or match with openings 22 of the slide bar. The support member preferably includes a vertical slot 46 extending from top to bottom thereof which is adapted to coincide with the vertical slot 26 of the horizontal slide bar. Similar to the first bracket, an angle bracket 48 is attached to the support member 42 in the manner shown and facing the first angle bracket. The bracket is supported by structural gusset 50. In the embodiment shown, a flexible cable 52 is attached at one end to the second bracket, specifically the structural gusset as shown, while the other end is adapted to retain a wedge locking element 54. The locking element is adapted to be inserted within vertical slots 46 of the second bracket and 45 26 of the slide bar 20. At the outward end of the second bracket some upwardly and outwardly extending lip members 56 are provided for co-action with the clamping pivot means generally designated by the numeral 58. The pivot device is provided with a handle portion 60 to which is affixed a first member 62 and pivotally supporting a second member 64 about pin 66. The first fixed member is provided with a yoke, as shown, for engagement over the slide bar 20 with pin member 24 which acts as a back-up for the pivot motion. Second member 64 is adapted to engage against support member 50 55 60 65

42 or the lip portions 56 of the second bracket for forcing the form members together until such position is reached where wedge locking element 54 can be inserted to lock the parts into place. Thereafter, the pivoting member 58 can be removed and used at the next adjacent support clamp. 5

In FIGURE 3 an alternate embodiment of this invention is described wherein a horizontal slide bar 70 comprises a single piece (a cross section of which is shown superimposed thereon) having a multiplicity of horizontal openings similar to that shown in FIGURES 1 and 2. At the one end, not shown, is fixed a first bracket similar to that generally designated 28, while a second bracket, as shown in FIGURE 1, is replaced by a wedge block 72 which is adapted to be yoked over bar 70 into a position 15 clamping the parts together and held by a pin 76 which is carried by the wedge block 72 by a cable 74.

In the operation of the apparatus of this invention, ordinarily the beam form members and kickers are in the position shown, being supported as shown in FIG. 4 20 by vertical T-brace supports 80 which extend between the floor and the bottom of forms 10, 12 and 14 and kickers 16 and 18. Spaced therebetween are the clamps of this invention. Usually, the spacing required between the first bracket and the second bracket, relative to the 25 vertical locking slots 26 has been established. Accordingly, the first bracket 28 is ordinarily affixed in a given position to the horizontal slide bar 20 by a key or pin 34. The second bracket is generally not in position as yet. The brackets may be preliminarily hung in place by one 30 man who positions the angle bracket 36 of the first bracket member over kicker 16. In such a position the clamp of this invention will hang balanced until raised to the substantially horizontal position wherein the second bracket 40 may be moved into its position and locked by 35 wedged element 54, which may be inserted and hammered downward into place if desired. In some instances it will be necessary to use the pivotal member 58 to force the beam support forms into a tight position and to position the second bracket 40 wherein wedge lock member 54 may be inserted within the vertical slots so provided. As such, an operator may stand within the space between the vertical side wall members 10 and 12 operating the pivotal means as desired and wedging the parts in position and thence moving to the next position. Of course, 40 to disassemble the reverse procedure is followed.

In the embodiment of FIGURE 3 it is merely necessary to attach the first bracket over the kicker on the left side, not shown, and thereafter insert the wedge yoke 72 in that space between the vertical side wall on the 50 right side and retaining pin 76 and hammer into place to adequately clamp the forms together.

Although this invention has been described with reference to the specific and preferred embodiments, it will be understood that minor changes in constructions, 55 combinations and arrangement of the parts may be made without departing from the spirit and scope of this invention as claimed.

What is claimed is:

1. Apparatus for clamping together unattached longitudinal vertical side wall forms spaced internally by a longitudinal horizontal bottom member with longitudinal rectangular kickers external of said side walls, said walls, member and kickers extending upward from a common bottom plane and supported at spaced intervals 65 upon vertical supports, comprising in combination therewith:

a horizontal rectangular conduit positioned transversely to said unattached forms, member, and kickers between said vertical supports, said conduit having a 70 plurality of parallel, horizontally spaced openings therein across the side of said conduit, and a plurality of spaced vertical slots in said conduit; a first bracket adjacent one kicker, said bracket comprising:

- (1) a support conduit telescopically movable along said horizontal slide,
- (2) at least one horizontal opening in said support conduit coincident to said openings in said horizontal slide to receive a pin therethrough whereby said support conduit is affixed to a given position adjacent one end of said slide conduit, and
- (3) an angle bracket attached to said support conduit and comprising a vertical leg terminating its upper end with a horizontal leg forming an inside corner for abutment against the respective outer corner formed by the vertical and horizontal edges of one of said kickers when said slide conduit is abutted against said forms along said common bottom plane;

a second bracket adjacent the other kicker comprising:

- (1) a support conduit telescopically movable along said horizontal slide,
- (2) a vertical slot in said bracket adjacent an outer end adapted to align with any of said vertical slots in said slide conduit,
- (3) upwardly and outwardly extending lips along said outer end of said bracket,
- (4) a wedged lock element adapted to be inserted in said aligned slots, said element retained to said bracket by a flexible cable, and
- (5) an angle bracket attached to said support conduit and comprising a vertical leg terminating its upper end with a horizontal leg forming an inside corner for abutment against the respective outer corner formed by the vertical and upper horizontal edges of the other of said kickers when said slide conduit is abutted against said forms along said common bottom plane; and

removable means pivotal between a fixed stop pin on said slide conduit and said lip on said second bracket to force said second bracket towards said first to clamp said forms whereby said vertical slots will be substantially aligned to receive said wedge lock element.

2. Unattached concrete beam forms comprising: a longitudinal horizontal member between longitudinal vertical side wall members which are between longitudinal and smaller rectangular kickers, said horizontal member, vertical side wall members and kickers extending upwardly from a common bottom plane and supported upon a plurality of spaced vertical supports, in combination with

a removable clamp positionable between said vertical supports and transverse to said longitudinal forms along the bottom to retain said beam forms in fixed position to receive said concrete,

said clamp comprising:

- (1) a horizontal slide bar abuttable with said common bottom plane of said beam forms and having spaced openings adjacent one end thereof,
- (2) a first angle bracket affixed to said bar adjacent the other end, said bracket defined by a substantially vertical leg terminating its upper end with a substantially horizontal leg, the inside corner formed by said vertical and horizontal legs facing toward said one end of said bar, and
- (3) a second angle bracket identical to said first bracket with the inside corner of said vertical and horizontal legs facing towards said first angle bracket, said bracket telescopically movable along said bar adjacent one end of said bar;

the inside corners of said first and second brackets abuttable with the top outer corners of said kickers when said horizontal slide bar is abutted against said common bottom plane; and

means to cooperatively lock said second bracket in a given position with respect to said spaced openings.
